Fig. 1

Fig. 2

Fig. 3

FIG. 1 is a front elevation of a decorative panel embodying my new design.

FIG. 2 is a transverse section, taken along line 2—2 of FIG. 1, showing a panel embodying my new design and having an unornamented rear surface.

FIG. 3 is a transverse section similar to FIG. 2 of a modified embodiment of the design of FIG. 1, the rear pattern being similar to the front, which is the only difference from FIG. 1.

The characteristic feature of my design resides in the pattern of the wood blocks.

I claim:

The ornamental design for a decorative panel or the like, as shown and described.
